UNITED STATES PATENT OFFICE.

CHARLES BERTHET, OF DETROIT, MICHIGAN, ASSIGNOR TO MUZZY-LYON COMPANY, OF DETROIT, MICHIGAN, A CORPORATION OF MICHIGAN.

METHOD OF MAKING BEARINGS OR THE LIKE.

Application filed June 18, 1921. Serial No. 478,771.

To all whom it may concern:

Be it known that I, CHARLES BERTHET, a citizen of the United States of America, residing at Detroit, in the county of Wayne 5 and State of Michigan, have invented certain new and useful Improvements in Methods of Making Bearings or the like, of which the following is a specification, reference being had therein to the accompanying 10 drawings.

The invention relates to the method of making bearings, bushings, etc., and refers particularly to bearings or the like having lined backs. The object of the invention is 15 to make with the minimum number of operations, a bearing or the like which comprises two true semi-cylindrical members. With this object in view, the invention resides in the novel features hereinafter set 20 forth.

In the drawings:

Figure 1 is an end view partly in section of a cylindrical bearing before being operated upon;

Figure 2 is a cross section through the bearing and showing a form of mechanism 25 for deforming the same;

Figure 3 is an end view of the separated semi-cylindrical members after the bearing 30 blank has been deformed and severed.

1 is a cylindrical bearing blank having the back 2 with the radial flange 3 at its outer ends, and the lining 4 within the back. The external and internal radii of the back 35 and lining are greater than the corresponding radii of the back and lining of the finished bearing; but, the thickness of the back and lining are the same as those of the back and lining of the finished bearing. The 40 cylindrical blank may be formed after any usual manner, such as, casting and machining the back, lining the same, and finishing to the desired radii.

The cylindrical blank 1 first has diametrically opposite sides flattened by suitable means such as the dies 5 which deform the blank to form end portions 6 having their radii reduced to the corresponding desired radii of the completed bearing, and also to 45 form the intermediate portion 7 connecting the end portions 6. This intermediate portion comprises two parts, each of which connects adjacent side edges of the end portions.

The next operation comprises the removing of the intermediate portion 7 as by cutting the blank. The radii of the cylindrical blank are sufficiently greater than the corresponding desired radii of the completed bearing and also the amount of deforming of the cylindrical blank is such that both compensate for the material removed in the intermediate portion so that each of the two end portions are true semi-cylindrical members and together form a 65 true cylindrical bearing.

The removal of the intermediate portion 7 may be accomplished by simply sawing the deformed blank or by a combination of sawing and milling or grinding depending 70 upon the desired finish of the abutting side edges of the two end portions 6. In either case, the amount of material to be removed is predetermined so that the radii of the cylindrical blank and also the amount of 75 deforming of this cylindrical blank is predetermined for each size of finished bearing.

What I claim as my invention is:

1. In the method of making bearings or 80 the like, the forming of a cylindrical blank of greater radius than that of the completed article, the deforming of the cylindrical blank to produce two end portions having their radii reduced to the desired radii of 85 the completed article and also an intermediate portion connecting said end portions, and the removing of the intermediate portion.

2. In the method of making bearings or 90 the like, the forming of a cylindrical blank having its wall corresponding in thickness to that of the completed article and having its inner and outer faces of greater radii than the corresponding radii of the completed article, the deforming of the cylindrical blank to produce two end portions having their radii reduced to the desired radii of the completed article and also an intermediate portion connecting said end 95 portions, and the removing of the intermediate portion, the radii of the tubular blank and the amount of deforming thereof being such as to compensate for the material in the removed intermediate portion.

In testimony whereof I affix my signature.

CHARLES BERTHET.
